No. 823,135.

PATENTED JUNE 12, 1906.

H. T. MURPHY.
COLLAR BUTTON.
APPLICATION FILED SEPT. 5, 1905.

UNITED STATES PATENT OFFICE.

HAROLD T. MURPHY, OF SPRINGFIELD, MASSACHUSETTS.

COLLAR-BUTTON.

No. 823,185.

Specification of Letters Patent.

Patented June 12, 1906.

Application filed September 5, 1905, Serial No. 276,934.

To all whom it may concern:

Be it known that I, HAROLD T. MURPHY, a citizen of the United States of America, and a resident of Springfield, in the county of Hampden and State of Massachusetts, have invented certain new and useful Improvements in Collar-Buttons, of which the following is a full, clear, and exact description.

This invention relates to improvements in 10 collar-buttons, and more particularly to the class thereof comprising locking means coöperating with the back of the button for clamping or binding the marginal portions of the collar or wrist band adjacent the buttonhole, 15 whereby notwithstanding any enlargement of the buttonhole the button cannot become accidentally displaced.

The object of the invention is to improve 20 collar-buttons of the class indicated to the end of acquiring simplicity and cheapness of construction and efficiency and convenience of use.

The invention consists in the constructions 25 and combinations of parts and the formations of certain of the parts, all substantially as hereinafter fully described, and set forth in the claims.

The improved collar-button is illustrated 30 in the accompanying drawings, in which—

30 Figure 1 is a side view thereof. Fig. 2 is a back view, the portion of the supplemental section comprised in the back being broken away for clearer illustration. Fig. 3 is a sectional view as taken on line 3 3, Fig. 2. Fig. 35 4 is a sectional view as taken at right angles to Fig. 3 and on the plane indicated by line 4 4, Fig. 2. Fig. 5 is a plan view of the main section of the back or back proper, together with a projected section thereof taken on line 4 5. Fig. 6 is a plan view of the flat spring 45 comprised in the locking collar-button, and Fig. 7 is a perspective view of one of the T-shaped lever members.

Similar characters of reference indicate 45 corresponding parts in all of the views.

In the drawings, A represents the back proper, B the post, and C the head of any suitable form and size and formed on or secured to the forward end of the post.

50 D D represent a pair of levers, the practical and specific form thereof being represented in Fig. 7, wherein it is clearly seen that each lever is of T form, the cross members a a thereof being cross-sectionally square, while the 55 portion b of the lever proper near the junction

of the transverse members a a is curved and the extremity d thereof widened.

The post as here shown is one having an arched base f to straddle the elongated aperture g in the back A, which aperture, as particularly shown in Figs. 3 and 5, has its location across the middle portion of the back and terminates within the opposite edge portions of such back, and the back, moreover, is made with depressions i i at right angles to 60 the length of the said aperture g and terminating at the opposite longitudinal boundaries thereof. These depressions are produced by sinking or displacing the thin metal from which the back is constituted, and in order 65 that these depressions may have the form of sufficiently deep troughs the metal at the margins of the depressions is upset, as indicated at j, and in the acquirement of this specific formation the thin metal back-plate 70 is made to assume the corrugated appearance 75 most clearly represented in Fig. 5.

The T-shaped levers are assembled in relation to the back so that their curved portions b are disposed adjacent and through the recess g, and the cross members a a are seated in the channels or depressions i i, and the spring G is so applied behind the back A as to be pressed against by the corners of the lever 80 cross members a a each time the levers are 85 swung a quarter-way around, more or less.

The spring G, as shown, is of flat form, is made of suitable thin metal, as steel or hard brass, and is anchored or in abutment at its ends and held against displacement and for 90 its spring action at all times against the said members a a, which, as apparent, are in substance cams.

The back-plate A is shown as having tongues h h struck up rearwardly from the 95 metal at the opposite marginal portions of such plate, which have interlocking engagement with the end recesses or niches k of the spring, so that the spring is constrained to remain always in its proper position of coac- 100 tion with the cross members of the levers.

m represents a supplemental back, which may be of any suitable metal or material, made in the form of a shallow cup and having the margins thereof return bent and overlap on the front marginal portion of the main plate or back proper of the button which carries the head - provided post. This supplemental back firmly engaged with the main plate A by reason of its convexity or swell 105 110

creates between it and the plate A a thin chamber, giving sufficient space for occupancy therein of the spring G and the lever members *a a* with clearance or freedom of deflection of the spring in consequence of the pressing of the parts *a a* having the cam-like actions relatively thereto.

The spring G of curved or bow form and having its ends in abutment at the opposite portions of the wall of the inclosed chamber at the junctions of the marginal portions of the supplemental back with the main back-plate is at all times effective as a yielding resistance to the movements of the levers.

15 The utility and mode of operation of the devices comprised in this improved button will be readily apparent from the drawings and the description of the parts hereinabove given; but it will be briefly mentioned that 20 the coaction between the spring behind the back-plate and the lever cross members is such as to firmly retain the levers in either of their given set positions, shown in full lines in Fig. 3, wherein the levers have their positions closely along the opposite sides of the post as appropriate at the time of engagement of the button through the buttonhole of the garment, and shown by dotted lines in Fig. 3 and full lines in Fig. 1, wherein the levers have their positions more or less nearly 25 parallel with and suitably close to the back to clamp or bind the portions of the fabric *x*, (which may be that comprised in a collar or wristband of a shirt,) adjacent the button-hole *y*, between the levers and the back.

30 In Fig. 1 the vertical parallel dotted lines at the right of the dotted-line representation of the shirt-collar band *x* are intended to indicate the overlapped buttonhole portions of 35 a collar, and the dotted lines still further to the right indicate a bow or necktie and the collar-button-engaging hook thereof.

I claim---

1. In a collar-button, a back having an 40 aperture, a post having a head, a pair of T-shaped levers being capable of being disposed along and at opposite sides of the post having their portions adjacent the junctions of the levers proper and their cross members 45 extended through said aperture, and having their cross members located behind the back, and a spring reacting behind the back and said cross members, and against which said cross members press on the swinging of the 50 levers.

2. In a collar-button, a back having an aperture, a post having a head, a T-shaped lever having the cross members thereof constructed as cams, the lever proper being capable of being disposed alongside the post, having the portion thereof near the junction of the lever with the cross members extended through said aperture, and a spring behind 55

the back against which the cam members of the lever press.

3. In a collar-button, a post provided with a head and a back to which the post is rigidly affixed, and said back having an aperture adjacent the post, and also having therein and at opposite sides of the margins of the aperture, depressions, a T-shaped lever having the portion adjacent the junction of the lever proper and its cross-head extended through said aperture, and having its cross-head seated in said depressions, and a spring behind the back against which the cross-head of the lever reacts.

4. In a collar-button, a back having an aperture, a post having a head, a pair of T-shaped levers capable of being disposed along 80 and at opposite sides of the post having their portions adjacent the junctions of the levers proper and their cross members extended through said aperture, and having their cross members located behind the back, and 85 a flat spring behind the back and having the extremities thereof immovably restrained relatively to the back and said cross members, and against an intermediate portion of which said members impinge on the swinging 90 of the levers.

5. In a collar-button, a thin metal back having an aperture, and tongues near its margin, the post having a head, a T-shaped lever having the cross members thereof constructed as cams, the lever proper being capable of being disposed alongside the post, having the portion thereof, near the junction of the lever with the cross members, extended through said aperture, and a flat spring behind the back, having its extremities engaged with said tongue, and against the middle portion of which the cam members of the lever press.

6. In a collar-button, a thin metal back 105 having an aperture, and "struck-up" tongues near its margin, the post having a head, a T-shaped lever having the cross members thereof constructed as cams, the lever proper being capable of being disposed alongside the 110 post, having the portion thereof, near the junction of the lever with the cross members, extended through said aperture, a flat spring behind the back, having its extremities engaged with said tongues, and against the middle portion of which the cam members of the 115 lever press, and a supplemental back of thin material marginally forwardly overlapping the back proper.

Signed by me at Springfield, Massachusetts, in presence of two subscribing witnesses.

HAROLD T. MURPHY.
